Primary Examiner — Mitchell Siegel(74) *Attorney, Agent, or Firm* — Dorsey & Whitney LLP(57) **CLAIM**

The ornamental design for a tee, as shown and described.

DESCRIPTION

FIG. 1 is a perspective view of a tee;

FIG. 2 is a front view of the tee in FIG. 1.

FIG. 3 is a back view of the tee in FIG. 1, opposite the front view of FIG. 2.

FIG. 4 is a side view of the tee, shown from the right of FIG. 2.

FIG. 5 is a side view of the tee, shown from the left of FIG. 2.

FIG. 6 is a top end view of the tee in FIG. 2; and,

FIG. 7 is a bottom end view of the tee in FIG. 2, opposite the top end view of FIG. 6.

Any broken lines in the drawings show environmental structure and define boundaries of the design, forming no part of the design to be patented.
